UNITED STATES PATENT OFFICE.

GEORGE H. BENEDICT, OF SCHENECTADY, NEW YORK.

EXTENSOMETER.

1,397,030.

Specification of Letters Patent. Patented Nov. 15, 1921.

Application filed October 8, 1919. Serial No. 829,351.

(FILED UNDER THE ACT OF MARCH 3, 1883, 22 STAT. L., 625.)

To all whom it may concern:

Be it known that I, GEORGE H. BENEDICT, a citizen of the United States, and a resident of Schenectady, county of Schenectady, 5 State of New York, have invented an Improvement in Extensometers, of which the following is a specification.

The invention described herein may be used by the Government, or any of its officers or employees in prosecution of work 10 for the Government, or by any other person in the United States, without payment of any royalty thereon.

My invention relates to an extensometer 15 device applicable for use in connection with the usual physical tests applied to materials employed in commercial manufacture.

Its objects are to provide an instrument 20 which is sufficiently delicate to read accurately to very small dimensions but which is also sufficiently substantial to possess wear resisting qualities so that the mechanism cannot be easily deranged or put out of working order.

25 A further object of this invention is to provide a precision measuring instrument of this type which may be readily applied to and removed from the test specimen.

In the description which follows reference 30 will be made to the accompanying drawings in which like reference numerals indicate corresponding parts throughout the several views.

Figure 1 is an elevation of my invention 35 with the parts in normal position and having the cover plate removed.

Fig. 2 is an elevation with the parts in extended position and having the cover plate removed.

40 Fig. 3 is an end view showing the cover plate in place.

Fig. 4 is a partial sectional view of a tool for making data marks.

The main working parts of my invention 45 are inclosed in the shallow box like casing 10 the top of which is formed with an interrupted and slightly depressed ledge 12 having threaded openings for the reception of machine screws which retain the detachable cover plate in place. The amount of depression of the ledge 12 is such that the cover plate is flush with the top of the working parts so as to retain them in operative relation and so that outside of the

cover plate is preferably flush with the top 55 of the sides of casing 10.

Riveted to the back plate of casing 10 are the duplicate, bearing members 14 having socket bearings which provide closely fitting journals for the cylindrical shaped lower 60 ends of registering bar supporting arms 5 and the cylindrical shaped upper ends of working bar supporting arms 4. The casing is preferably made of bronze and the bearing members 14 and arms 4, 5 of steel so 65 that the rounded ends of arms 4, 5 and the corresponding bearing surfaces may be hardened if desired in order to furnish wear resistant surfaces but this is not necessary since the bearing surfaces provided are 70 ample and if any wear should occur it will be uniform throughout the bearings and will not therefore impair the accuracy of the mechanism.

The lower cylindrical shaped ends of arms 75 4 are journaled in bearing sockets at opposite ends of working bar 1. All of the bearing sockets of this device are formed so that the material forming the socket extends a considerable distance past the semi-circle at any section. Therefore when the cylindrical ends of the supporting arms are inserted into the sockets and the cover plate is secured in place flush against the top of the socket bearings, the supporting arms 4, 5 80 85 are securely held in operative position within the socket bearings 14.

In view of this connection of the working bar 1 with registering bar 3 through arms 4, socket bearings 14 and arms 5 these bars are 90 always substantially parallel.

Projecting from the upper side of bar 1, 95 is a lug 17 and projecting from bar 3 is a lug 18. A pivot pin 15 projects upward from the back plate of casing 10 and provides a pivot for multiplying lever 2. The multiplying lever 2 is of such thickness at its hub portion as to fit snugly under the cover plate so that it is retained in operative position thereby. The pivot 15 is located 100 near lug 17 so that the movement communicated to the lever by lug 17 is transmitted to lug 18 in multiplied form which is preferably some simple multiple as one to ten.

Secured to the lower side of working bar 105 1 and preferably integral therewith is a hardened point 9 called the movable point and secured to the lower side of the casing

10 is the hardened point 11 called the fixed point, the function of which points will be hereinafter described. When the working bar 1 is in operative position the point 9 5 projects through an elongated slot formed in the side wall of casing 10. The points 9 and 11 are of such length as to extend the same distance from the side wall of the casing.

10 The registering bar 3 has at one end an upright split extension 19 which is threaded for engagement with adjusting screw 7. The extension 19 projects through and is movable in an elongated opening in the 15 upper side of casing 10. The screw 7 is adjusted so as to just contact with the end of operating stem 21 of a micrometer indicator having a graduated dial and a pointer which is capable of making a complete revolution for a small longitudinal movement of the stem, and thus give an easily readable 20 measurement of a very small quantity. The specific form of indicator forms no part of my invention it being understood that any 25 suitable type of commercial indicator can be used without departing from the spirit or scope of my invention. The indicator shown on the drawing is secured to the upper side of casing 10 by means of 30 screws 20.

A holding block extends below the casing and is secured to the back plate of casing 10 in any suitable manner as by means of screws 22. The holding block having the 35 short portion 24 and long portion 23 is L-shaped. The portion 24 is formed with a central hole which is threaded for screw 25. The long portion 23 is slotted and the two parts of this slotted portion are slidably 40 engaged by a V-block clamp attachment which comprises the wide V-clamp, and a wide rear extension 26. The rear extension is inserted while in endwise position through the slotted portion and then the V- 45 clamp attachment is turned to upright position. Since the portions 6 and 26 of the clamp attachment are wider than the slot, the clamp attachment is slidably supported. The screw 25 extends upward through a 50 hole in extension 26 and is retained therein against rotation by means of pin 27. A nut 28 engages the threads of screw 25 and abuts against one side of portion 24. A spring 29 surrounding screw 25, is compressed between stationary member 24 and extension 26 and thus tends to force the V-clamp block upward.

Where a large number of test specimens of a specified form are used and the data 60 marks are originally a given distance apart, a marking tool similar to the type shown in Fig. 4 may be advantageously used, in which the marking points 30 and 31 are the given distance apart, and the interior of the 65 tool of the general contour of the body of

the test specimen, such tool also having the flattened head 32 on which impact is made in order that the points 30 and 31 may make proper indentations or data marks in the test specimens.

In operation the data marks are first made on the test specimen, preferably by the device shown in Fig. 4, and the test piece is then placed in the testing machine. The extensometer is then placed upon the test 75 piece, the two points 9 and 11 being placed in the data marks, and the nut 28 adjusted so that the extensometer is held in place by the V-block clamp which is acted upon by spring 29 with sufficient force to keep the 80 points 9 and 11 firmly seated. The screw 7 is then adjusted so that when a slight initial stress is placed on the test piece a minute elongation will be recorded. The screw 7 is then delicately adjusted until the indicator 85 reading is brought back to zero.

As the stress is applied to the test piece the movable point 9 moves as the metal elongates thereby causing the point 9 and working bar 1, to move with the elongations of 90 the metal. The multiplying lever 2, transmits this movement to the registering bar 3 in an increased ratio of preferably one to ten. This increased movement of recording bar 3 is registered in multiplied form by the 95 indicator 8, by means of screw 7 which moves with bar 3 contacting with the stem 21 of the indicating instrument. To prevent injury to the mechanism by the shock that occurs when the test piece breaks the extensometer is usually disconnected after the elastic limit of the material of the test piece has been reached.

This instrument gives a definite, and accurate indication of the elastic limit of the 105 material either by noting successive readings given by equal load increments in order to find the point where elongation ceases to be proportional to the tensile stress or by returning to the initial load after each additional stress until permanent set is indicated.

Having described my invention, what I claim as new and desire to secure by Letters Patent is:—

1. An extensometer comprising a casing having a point fixed with reference thereto, a movable working bar mounted in said casing and having a second point secured thereto, a lug on said bar, a register operating bar movably mounted in said casing and having a projecting lug and a pivot lever coacting with said lugs.

2. An extensometer comprising a casing, intermediate socket bearings secured to said casing, a working bar having socket bearings, supporting arms for said working bar mounted in said socket bearings and a cover plate for retaining said supporting arms in operative position.

3. An extensometer comprising a casing,

- intermediate socket bearings secured to said casing, a registering bar having socket bearings, supporting arms for said registering bar mounted in said socket bearings, a working bar, a pivoted lever for communicating motion from said working bar to said registering bar and a cover plate for retaining said supporting arm and pivoted lever in operative position.
- 10 4. An extensometer including a casing having a point fixed with reference thereto, a working bar having the movable point se-

cured thereto, a registering bar, means for communicating motion from said working bar to said registering bar, an indicator and 15 means adjustable in said registering bar, for actuating said indicator.

5. In an extensometer, a casing containing a movable working bar, a registering bar, a pivoted lever, supporting arms 20 for said bars, and a removable cover plate for said casing for retaining said parts in operative position.

GEORGE H. BENEDICT.
